UNITED STATES PATENT OFFICE.

CHARLES FISHER, OF OAK PARK, ILLINOIS, ASSIGNOR, BY MESNE ASSIGNMENTS, TO THE AUTOMATIC RECORDING SAFE COMPANY, OF CHICAGO, ILLINOIS; A CORPORATION OF ILLINOIS.

SAVINGS-BANK.

1,102,256.

Specification of Letters Patent.

Patented July 7, 1914.

Application filed April 7, 1903. Serial No. 310,529.

To all whom it may concern:

Be it known that I, CHARLES FISHER, a citizen of the United States, residing at Oak Park, in the county of Cook and State of Illinois, have invented certain new and useful Improvements in Savings-Banks, of which the following is a specification, reference being had to the accompanying drawing, forming a part thereof.

The main objects of this invention are to promote the habit of saving money by providing a convenient receptacle therefor into which coins of various denominations, and bills if desired, can be readily inserted, but from which they cannot be removed without a key, and generally to improve the construction and operation of devices of this class.

It consists in certain novel features of construction and in the peculiar arrangement and combinations of parts as herein-after particularly described and pointed out in the claims.

In the accompanying drawing like characters designate the same parts in the several figures.

Figure 1 is a vertical section on the line 1, 1, Fig. 2, of a bank embodying the invention; Fig. 2 is a plan view of the bank; Fig. 3 is a horizontal section on the line 3, 3, Fig. 1; Fig. 4 is a side elevation of a portion of the bank as viewed from the left with reference to Figs. 1, 2 and 3; Figs. 5, 6 and 7 are detail views of the lock; Fig. 5 being a side elevation, Fig. 6 a central vertical section on the line 6, 6, Fig. 7, and Fig. 7 a cross section on the line 7, 7, Fig. 5, and Figs. 8 and 9 are views showing the opposite sides of a graduated gage or measure for determining the number and amount of coins in the several compartments of the bank.

The bank, which is preferably made of cylindrical form, comprises two main parts, a base *a* and an inclosing case or cover *b*. Upon the base are mounted a number of vertical cylindrical coin receptacles or holders *c*, *d*, *e*, *f* and *g*, having slots or openings in their outer sides from top to bottom. From the inside of the top of the cover *b* are suspended by spiral springs *h*, disks *i* which are loosely fitted in the several coin compartments or receptacles *c*, *d*, *e*, *f* and *g*.

The cylindrical coin receptacles are made of different diameters to correspond with

coins of such denominations as the bank may be designed to receive, and they are preferably arranged side by side as shown in Figs. 2 and 3, but the number and arrangement of such receptacles may be varied according to the use that is to be made of the bank. In the present case a receptacle *c* for pennies, a receptacle *d* for silver half dollars, a receptacle *e* for quarters, a receptacle *f* for dimes, and two receptacles *g* for nickels are shown in the order named. An opening is left between the penny and last nickel receptacles for the insertion of bills into the space between the coin receptacles.

The base is formed with oblique guide-ways *j* leading upwardly from its periphery into the several coin receptacles and plane or flat coin rests or supports *w* at the bottoms and inner sides of the receptacles perpendicular to their axes, and the cover *b* is formed in the lower part of its depending rim with openings which register with these guide-ways. The opening and guide-way into each receptacle are made of a depth and width to correspond with the thickness and diameter of the coin for which such receptacle is intended.

For the insertion of bills, the cover is formed in one side with an opening between the coin receptacles *c* and *g*, and is provided on the inside with a tube *k* registering with said opening and terminating at its inner end with slightly inturned serrations or points which prevent the withdrawal of the bills from the bank through said opening.

The cover is secured to the base by a lock or fastening comprising a spring *l*, attached at its lower end in the present instance to the inner side of the coin receptacle *d*, and bent inwardly at its upper end at right angles thereto, and inclined guide and keeper *m* attached to the top of the cover inside thereof, as shown in Fig. 1. These parts are so arranged with relation to each other that when the cover is carried into place over the base the hooked end of the spring *l* will be deflected by the guide *m* and brought into engagement with its upper edge, and thereby automatically locking the parts together. With the guide and keeper *m* is formed a cylindrical socket or case *n* in which is fitted a key barrel *o* which is exposed at its upper reduced end through an opening in the cover. This barrel is formed with a longitudinal slot opening

through the ends and one side thereof to receive a flat key *p*, which has a bit *q* at the end adapted to engage with and force the hooked end of the spring *l* off from the keeper *m* when a quarter turn is given to the key in the proper direction, the movement of the key in both directions being limited by stops *r* and *s* on the lower end of the barrel case or socket, as shown in Figs. 1, 5 5 and 7. The inclined guide and keeper *m* is formed on each side with wings or guards *t* by which it is connected with the lower end of the barrel case *n*. These wings or guards serve not only to firmly support the 10 guide and keeper *m*, but also to prevent bills which are inserted in the bank from becoming entangled with the lock and interfering with its operation.

The main parts of the bank may be and 20 preferably are made of sheet metal, and the edges of the coin receptacles next to the vertical openings in their outer sides are flanged or bent outwardly, as shown, so as to stiffen and strengthen said receptacles and at the 25 same time close the spaces which would otherwise be left between them and the surrounding rim of the cover or case *b*, as shown in Fig. 3.

The bank when closed does not expose its 30 contents to view and is what is known as a "blind bank". To enable the depositor or holder to determine the number of coins and the amount of money in coin which the bank contains, the top of the cover *b* is formed 35 with a slot *u* over each coin receptacle, as shown in Fig. 2, and a gage or measure *v* adapted to be inserted through said slots into the bank, and graduated on opposite sides, as shown in Figs. 8 and 9, to indicate 40 the number and amount of coins contained in the several coin receptacles, is provided. This gage or measure may be conveniently made of a thin strip of metal and perforated at one end so as to be placed on a key-ring 45 and carried in the pocket of the depositor or holder of the bank, it being the intention that the key *p* of the bank shall be kept in the possession of an officer or employee of the savings institution with which deposits 50 are to be made.

To prevent tipping the coins contained in the bank, particularly when there is but one or a few in each receptacle, so that they may be removed through the oblique guides and 55 openings *j* by inserting the gage *v* or other instrument through the slots *u* against the outer parts of the disks or coin followers *i*, the springs *h* and the slots *u* are located between the centers of the several coin receptacles and the center of the bank and said guides are made to join the coin rests or supports at the bottoms of the receptacles at an angle thereto outside of their centers, so that the gage or measure *v*, or any other instrument inserted through such slots, cannot

come in contact with the outer parts of said disks or followers which overhang the inclined or oblique coin guide-ways *j* and tip the underlying coin or coins into position to pass out through said guide-ways, the gage *v* or other instrument being guided and confined within the spiral springs *h*.

The springs *h* may be conveniently attached to the cover *b*, as shown in Figs. 1 and 4, by prongs punched from the slots *u*, and they may be attached to the disks or followers *i* at their lower ends in a similar manner by prongs struck up from said disks, as shown in Figs. 1 and 3.

In the use and operation of the bank, coins of the various denominations are inserted through the oblique openings and guide-ways *j* into the lower ends of the proper receptacles *c*, *d*, *e*, *f* and *g*, underneath the disks or followers *i*, which under the tension of the springs *h* press the coins into a position parallel with the plane of the base when they are completely within the bank and retain them in that position, tiers or piles of coins being thus built up from the bottom and the coins being held flatwise one upon another in the several receptacles. A coin being thrust into a receptacle through the upwardly inclined guide way *j* at its lower end, crowds the preceding coin or coins therein upward against the opposing spring pressed follower, thereby making room for itself in the bottom of the tier or pile.

To determine at any time how many and what amount of coins are contained in any given receptacle, as for example in the receptacle *d* for half dollars, the gage *v* is inserted through the slot *u* over that receptacle, and the reading on the scale, marked "50," is taken. If eight divisions on the scale appear above the cover, there are eight fifty cent pieces, amounting to four dollars, in the receptacle. The number and amount of coins in the other receptacles is determined in like manner by the corresponding scales 100 on the gage or measure *v*.

When any compartment of the bank is filled, or it is desired to make a deposit, the bank is taken to the proper depository and opened by means of the key *p* which is held by such depository. The key being inserted in the barrel *o* when the slot therein is in register with a notch in the cover, as shown in Fig. 2, is then turned with the barrel to the right against the stop *r*, thereby carrying its bit *q* into engagement with the hooked end of the spring *l* and thrusting it off from the keeper *m*. To remove the key it is turned back against the stop *s* when the slot in the barrel *o* will register with the notch in the cover and a corresponding notch in the lower end of the barrel case or socket *n*. Notches are made in the key to receive the edge of the cover *b* around the barrel opening and the edge around the opening in the 120 125 130

lower end of the barrel case which serve as wards for the lock.

When the cover is removed from the bank the coins may be removed from each of the 5 several receptacles separately without disturbing the piles in which they are arranged, by grasping the top and bottom of each pile through the opening in the outer side of the receptacle, or if all of the receptacles are 10 filled or nearly filled, they may be emptied simultaneously without disarranging the piles by covering them with a board or plate, inverting them thereon and then removing the base with the coin receptacles, 15 leaving the coins in piles on the board or plate.

To determine the proper position of the cover *b* and to guide it into place on the base *a* so that the followers *i* will register with 20 their corresponding receptacles *c*, *d*, *e*, *f* and *g*, and the parts *l* and *m* of the lock or fastening will be in the proper relation to each other, the attachment plate at the outer end 25 of the tube *k* is extended on each side to engage with the adjacent flanges on the receptacles *c* and *g*, as shown in Fig. 3, the space between said flanges being the only one of sufficient width to receive said plate.

It will be observed that the coin slots in 30 the cover registering with the oblique guide ways *j* forming shoulders in the base being curved, and corresponding in width vertically with the thickness of the coin, as shown in Fig. 4, and the lower edges of the slots projecting above the lower inclined faces of the 35 guide ways *j*, and as shown in Fig. 1, the coins if tipped by means of an instrument inserted through the slots or by other means cannot be withdrawn from or shaken out of 40 the bank on account of said shoulders with which their edges would engage.

The bank need not necessarily be made of cylindrical form, although this is the preferred form, and various changes may be 45 made in the details of construction and arrangement of parts without departing from the spirit and intended scope of the invention.

I claim:

50 1. In a savings bank, a cylindrical coin receptacle having a flat transverse coin-rest and an inclined coin guide-way inside the receptacle and at an angle to the coin-rest to receive a coin through an adjacent opening 55 in the side of the bank, the opening into said guide-way being below the plane of the coin-rest and the opening of the guide-way into the receptacle being outside of its center, and a yielding follower in the receptacle 60 parallel with the flat coin-rest and lying across said guide-way, substantially as described.

2. In a savings bank, the combination of a base having a number of cylindrical coin 65 receptacles mounted thereon, each formed

with a longitudinal slot of less width than the diameter of the receptacle and having a flat transverse coin-rest and an inclined coin guide-way lying within the receptacle, on the side where the slot is formed and at an angle to the coin-rest, the opening into each guide-way being below the plane of the coin-rest and the opening of the guide-way into the receptacle being outside of its center, a cover adapted to inclose said receptacles, and a fastening detachably securing the cover to the base, substantially as described. 70

3. In a savings bank, the combination of a base having a number of cylindrical coin-receptacles provided with flat transverse coin-rests, and upwardly inclined coin guides extending obliquely into one end of said receptacles at an angle to said rests, the openings into said coin-rests being below the plane of the coin-guides and the openings of the coin-guides into the receptacles being outside of their centers, a removable cover adapted to inclose said receptacles, disks or followers loosely fitting in said receptacles above said coin-rests and across said guides, springs tending to press said disks toward one end of said receptacles, and a fastening for securing the cover to the base, substantially as described. 80

4. In a savings bank, the combination of a coin receptacle having a coin slot or guide entering one end thereof obliquely and an opening through the other end, a coin follower loosely fitting in said receptacle, a spiral spring attached at one end to said follower with the axial opening through the spring back of the opening of the oblique coin guide into said receptacle and at the other end to the opposite end of the receptacle around the opening therein and tending to press the follower toward the receiving end of the receptacle, said spring and the opening in the end of the receptacle being so positioned in relation to each other 100 to permit a graduated gage to be inserted through said end opening and spring to indicate the number of coins in said receptacle, substantially as described. 105

5. In a savings bank, the combination of a base provided with a number of cylindrical receptacles with flat transverse coin rests at the bottom for coins of different denominations, and having coin slots or guides opening obliquely into the lower ends of the 110 receptacles at an angle to said rests for the insertion of coins, a removable cover adapted to inclose said receptacles and having an opening over each receptacle, followers loosely fitting in said receptacles above said 115 coin rest, and spiral springs connecting said followers with the cover around the openings therein, and out of line with the openings of the coin slots or guides into said receptacles, said springs and the openings in 120

the ends of the receptacles being so disposed in relation to each other to permit a graduated gage to be inserted in said openings and springs to indicate the number of 5 curing the cover to the base, substantially scribed.

6. In a savings bank the combination of a base provided with a number of vertically slotted cylindrical coin receptacles arranged 10 side by side, forming an intermediate bill receptacle and having coin slots or guides opening into their lower ends, an open space being left between two coin receptacles on one side of the bank, a removable cover 15 adapted to close said receptacles, the wall of the bank having an opening into said space for the insertion of bills, and a lock for securing the cover to the base, substantially as described.
- 20 7. In a savings bank, the combination of a base provided with coin receptacles, a removable cover adapted to inclose said receptacles, and a lock comprising a hooked spring attached to one part, an inclined 25 guide and keeper attached to the other part in position to be engaged by said hooked spring, and a key-barrel arranged adjacent to said keeper and exposed at one end through an opening in the inclosing wall, 30 said barrel being slotted to receive a key which has a bit for forcing the hooked spring off from said keeper, substantially as described.
8. In a savings bank, the combination of 35 a base provided with a number of coin receptacles arranged side by side to form an intermediate bill receptacle and having coin slots or guides opening into their lower ends, a removable cover having a depending rim 40 adapted to surround and inclose said receptacles and provided with an opening in one side into the bill receptacle, said opening having a tubular extension inside terminating in teeth or points to prevent withdrawal 45 of bills, and a lock comprising a hooked spring attached to the base, an inclined guide and keeper attached to the cover in position to be engaged by said hooked spring, and provided on each side with

wings or guards, a slotted key-barrel fitted 50 to turn in a case adjoining said keeper and exposed at one end through an opening in the cover, and a key fitted in said barrel and having a bit adapted to force the hooked spring out of engagement with said keeper, 55 substantially as described.

9. In a savings bank, the combination of a coin receptacle having a flat transverse coin-rest at one end of the receptacle extending partially across the receptacle and a 60 lateral coin slot or guide-way opening obliquely into one end of the receptacle at an angle to said coin-rest and inclined upwardly toward the opposite end of said receptacle for the insertion of a coin, the opening into said guide-way being below the plane of the coin-rest and the opening of the guide-way into the receptacle being outside of its center, and a coin follower loosely fitted in said receptacle parallel with and extending 65 beyond said coin-rest and over said guide way and adapted to hold the coins therein parallel with the plane of the rest, substantially as described.

10. In a savings bank the combination 70 of a cylindrical coin receptacle having a flat transverse coin rest at one end and a longitudinal slot or opening in one side of less width than the diameter of said receptacle and a lateral coin guide way or slot projecting obliquely into one end thereof at an angle to said rest for the insertion of a coin, the opening into said guide-way being below the plane of the coin-rest and the opening of the guide-way into the receptacle being outside of its center, a coin follower loosely fitted in said receptacle, above said coin rest and across said guide-way, and a spring tending to press said follower toward the receiving end of the receptacle, 80 substantially as described.

In witness whereof I hereto affix my signature in presence of two witnesses.

CHARLES FISHER.
